UNITED STATES PATENT OFFICE.

LÉON JEAN JORET, OF PARIS, FRANCE, ASSIGNOR TO SOCIÉTÉ H. ARQUEMBOURG
JORET & CIE., OF PARIS, FRANCE.

CARBURETER.

1,259,105.

Specification of Letters Patent. Patented Mar. 12, 1918.

Application filed July 23, 1914. Serial No. 852,634.

To all whom it may concern:

Be it known that I, LÉON JEAN JORET, of 71 Rue du Moulin Vert, in the city of Paris, Republic of France, have invented 5 Improvements in Carbureters, of which the following is a full, clear, and exact description.

In ordinary carbureters the fuel provided by the spraying nozzle is generally only 10 drawn along by the current of air sucked in; now, by reason of the great speeds required from present motors (2,000 to 3,000 revolutions per minute), it is necessary to admit in the same time, a very large volume 15 of air, and consequently, to give to the air inlet orifice, a relatively large diameter; but this orifice of large diameter involves an inconvenience when the motor is running without load at a slow speed (200 revolutions for example), the throttle valve being 20 almost completely closed, because the speed of the air is so much reduced that the fuel which finds its way into the apparatus and which, in consequence of the low speed of 25 this air, has not been atomized, can no longer be regularly sucked in.

This inconvenience is so much the greater in ordinary carbureters having a vertical axis, by reason of the effects of the weight 30 which opposes the ascending motion of the fuel.

This results in accumulations of fuel above the throttle valve, and at the time of the sudden openings of this latter, it sometimes 35 happens that this excess of non-atomized fuel is drawn in bodily by the current of air which, at this moment, is moving with great speed, and there follows from this an unequal carburation, which frequently sets up 40 a series of misfires and even the stoppage of the motor.

The present invention relates to an arrangement of carbureter having for its object to remedy this inconvenience.

45 This arrangement of carbureter is combined in such manner as to utilize the effect of weight to contribute to bring the fuel which would not have been volatilized at its exit from the spraying nozzle, to a conveniently chosen point where the air sucked in by the motor under a low depression, will be obliged to pass when the throttle valve is slightly opened, in such manner that this fuel is immediately atomized by the very 50 rapid passage of this air.

The accompanying drawing represents, by way of example, the present arrangement of carbureter.

Figure 1 represents, in vertical section, a mode of construction of the present carbureter, having only one spraying nozzle, the throttle valve being in its closed position.

Fig. 2 represents it in the case in which the throttle valve is slightly opened.

Fig. 3 represents the present arrangement 65 of carbureter with additional air inlet.

Figs. 4 to 8 show a carbureter constructed according to the present invention, having two spraying nozzles.

Fig. 4 is a vertical section drawn on the 70 line A—B of Fig. 5; Fig. 5 is a horizontal section drawn on the broken line C—D of Fig. 4; Fig. 6 is a vertical transverse section drawn on the line E—F of Fig. 5; Fig. 7 is a vertical section drawn on the line G—B 75 of Fig. 5; Fig. 8 is a detail view showing, in plan, the plug of the throttle valve.

As shown at Fig. 1, the present arrangement of carbureter comprises a carbureting chamber *a*, of conical form and inclined to 80 the horizontal to such an angle that, even when applied to a vehicle, if the apparatus takes a great inclination consequent on the profile of the road, the fuel furnished by the spraying nozzle *b* and not atomized, 85 flows always by the simple effect of weight, following the line of greatest incline toward the throttle valve interposed in this inclined carbureting chamber.

This throttle valve opens at its lower part, 90 as seen in the drawing and comprises a plug *c*, which has an interior conical channel *c'*, the generating lines of which merge with those of the carbureting chamber *a* when the valve is fully open.

95 By reason of the conicity of the channel *c'* of the valve plug *c*, the orifice of this plug, which is toward the motor, has a greater diameter than that of the orifice situated toward the spraying nozzle *b*; consequently, when the valve is simply lightly opened toward the spraying nozzle, it presents a larger opening toward the motor, in these conditions there exists in the interior of the valve plug, as will be seen later on, 100 a depression about equal to that of the suction pipe.

105 The valve plug *c* is further provided with a small groove *c''*, arranged so as to establish a permanent communication between 110

the lowest point of the valve body and the suction tubing leading to the motor; there can thus be no accumulation of fuel in the valve, as will be hereinafter explained.

5 The spraying nozzle b is fed from a suitable constant level reservoir d .

The working of this arrangement of carbureter is as follows:

We will designate by P , the atmospheric 10 pressure which exists at the entrance of the carbureting chamber a ; P^s the depression existing in the suction tube leading to the motor; P^1 and P^2 the intermediary depressions existing, respectively, in the part

15 of the carbureting chamber situated immediately in front of the throttle valve, and in the interior of the plug c of the latter.

For starting, the throttle valve is slightly 20 opened, so as to create in the carbureting chamber a depression P^1 sufficient for the sucking up of the fuel necessary for feeding the motor.

At this moment the speed of the air, as 25 has been above stated, is too small to suitably atomize the fuel, a part of which falls back into the carbureting chamber and flows along the line of greatest incline toward the throttle valve.

At the time of slow working the depression 30 P^1 is little different from the atmospheric pressure, and the depression P^2 is about equal to the depression P^s , but there exists, on the contrary, between P^1 and P^2 , a difference of depression which attains 35 about $\frac{1}{2}$ of an atmosphere; under the influence of this depression, the air passing through the slightly open throttle valve, at a speed of about 100 meters per second, produces an atomization of the non-volatilized 40 fuel which has flowed away, as has been above stated. Further, the atomized fuel entering the channel C^1 of the valve plug in a medium of small depression, volatilizes almost immediately.

45 If a small quantity of fuel resisting atomization and volatilization just above mentioned, falls to the lower part of the throttle valve body, this fuel under the effect of the difference of the depressions P^2 and P^s , 50 is immediately sucked up, and at the same time broken up and atomized again, by the effect of the current of air through the groove c^2 , and finally atomized on its arrival in the suction tube leading to the 55 motor.

The atomization of the fuel is effected, therefore, by the present arrangement, in the form of a cascade, as shown in Fig. 2.

When progressively opening the valve to 60 pass from slow speed to normal working, the difference between the depressions P^1 and P^2 continues to diminish; on the contrary the difference between the depression

P^1 and atmospheric pressure P increases; 65 the speed of the air in the region of the

mouth of the spraying nozzle, therefore accelerates, and there follows from this a more perfect atomization of the fuel which leaves the latter. There is, therefore, no longer so much need of complementary atomizations capable of being produced, as has been above said, in the interior of the valve and immediately at the outlet of the same; nevertheless, these complementary atomizations preserve their effect just to 75 the moment when the valve is completely opened and when the atomization around the spraying nozzle is accomplished in a complete manner.

Fig. 3 shows the present arrangement of 80 carbureter combined in such manner as to comprise an additional air inlet.

The carbureter comprises in this case, two concentric carbureting chambers, an interior chamber a^1 , into which the spraying nozzle b opens, and an exterior chamber a^2 which carries the additional air intake e and upon which is interposed the throttle valve. The additional air intake 85 e will be of any suitable type, either with 90 one or several valves, ball or other valves.

A space is reserved between the two chambers a^1 , a^2 for the passage of the air admitted by the additional air inlet. The axis of the two chambers a^1 , a^2 is inclined 95 so that the fuel issuing from the spraying nozzle b , and which has not been atomized and volatilized, flows, at first, the length of the chamber a^1 , then falls onto the lower side of the chamber a^2 , and is thus conducted to the throttle valve; the volatilization 100 of this fuel is produced in the above described conditions.

Figs. 4 to 8 show the application of the 105 present invention to a double carbureter.

In this mode of construction the main carbureter is constituted, in principle, as has already been described; to this main carbureter is added a secondary carbureter arranged in the following manner:

The body of the apparatus has a conduit 110 f (Fig. 7) which opens at one end into the atmosphere and at the other end into the throttle valve body through the orifice f^1 ; this conduit f constitutes the carbureting 115 chamber of the secondary carbureter. Into this carbureting chamber f enters a spraying nozzle b^2 , fed, like the spraying nozzle b^1 of the main carbureter, by the constant level reservoir d .

The plug c of the throttle valve has a small conduit c^3 for the purpose of establishing communication of the chamber f of the secondary carbureter with the interior channel c^1 of the said plug, and a 125 notch c^4 for the purpose of facilitating the passage from the small to the large carbureter.

This conduit c^3 is arranged in such manner as to uncover, in the position corre- 130

sponding to the slow speed, only a small part of the orifice f^1 of the secondary carbureter (Fig. 7).

When the plug c is rotated in the direction of the arrow represented in Figs. 4 and 7, to pass from slow speed to normal working, the main carbureter is, at first, held closed, and the plug c uncovers the orifice f^1 ; the free section of passage from the secondary carbureter thus increases considerably, in such manner that the latter, which is furnished with no arrangement of correction, compensation or automatic regulation, sends into the admission conduit to the motor, a very rich carbureted mixture which, at the time of the progressive opening of the main carbureter, and thanks to the notch c^4 , carburetes the air, or the air too slightly carbureted furnished by the latter at the commencement of its opening, and thus strengthens the carburation of said air up to the moment when the main carbureter has attained its normal working; in these conditions the passage from slow working to normal working is effected without too sensible impoverishment of the carbureted mixture, and consequently without risk of stopping the motor.

When the motor works at its normal speeds, the rotation of the plug c is completed; the secondary carbureter is thus placed out of operation and the main carbureter works alone.

The notch c^4 may be more or less prolonged so as to permit of keeping in operation, during a longer or shorter time, by means of the plug c , simultaneously or not, the two carbureters.

When the plug c is rotated in the reverse direction to that of the arrow represented at Figs. 4 and 7, this plug closes at the same time, the main carbureter and the secondary carbureter, and thus enables all consumption of fuel to be avoided when a vehicle descends a hill by the action of its weight.

This special arrangement of control enabling the two carbureters to be successively or simultaneously placed in operation in the above described conditions, can also be applied to all arrangements of carbureters, vertical or otherwise.

It is well understood that the modes of construction above described are only given by way of example and that the forms, dimensions and details of construction of the present arrangement of carbureter may be

modified without changing the principle of the invention.

Claims:

1. In a carbureter, an inclined carbureting chamber, a spraying nozzle projecting into the chamber, and a throttling plug valve at one end of the said chamber and having a conical channel, the smaller end of which is toward the spraying nozzle and the larger end toward the motor. 60

2. In a carbureter, an inclined carburation chamber,—a throttling valve arranged on the latter, the interior channel of the plug of the valve being inclined so that said valve opens at its lower part toward the carburation chamber and being conical so as to provide a larger section of opening toward the motor than toward the spraying nozzle,—a 70 small groove provided on a part of the periphery of the valve plug toward the motor and adapted to establish a constant communication between the lowest point of the valve and the suction tube of the motor. 75

3. In a carbureter, a main carbureter having an inclined carburation chamber,—a secondary carbureter having also an inclined carburation chamber,—a throttle valve in which end the said carburation chambers,— 80 a small conduit provided in the plug of the valve, opening on the one hand in the inner channel of said plug and, on the other hand, at the periphery of this plug through an orifice adapted to uncover, in the position 90 of the plug corresponding to slow speed, but a fraction of the orifice of the secondary carburation chamber, and to completely uncover said orifice when the plug is turned for putting the main carbureter into opera- 95

tion,—a notch provided on the periphery of the plug of the throttle valve at the point where opens the said small conduit and adapted to maintain in operation the secondary carbureter during a certain time 100 when the plug of the throttle valve is turned for putting the main carbureter into operation,—and a slot provided on a part of the periphery of the plug toward the motor and adapted to establish a constant communication between the lowest point of the throttle valve and the suction tube of the motor. 105

The foregoing specification of my improvements in carbureters signed by me this ninth day of July, 1914.
